UNITED STATES PATENT OFFICE.

JAMES DAVIDSON, OF CENTRAL CITY, COLORADO.

WRENCH.

SPECIFICATION forming part of Letters Patent No. 289,506, dated December 4, 1883.

Application filed April 27, 1883. (Model.)

To all whom it may concern:

Be it known that I, JAMES DAVIDSON, of Central City, in the county of Gilpin and State of Colorado, have invented a new and Improved Wrench, of which the following is a full, clear, and exact description.

My invention consists in a socket-wrench provided with expansion-jaws, and a loose sleeve constructed to contract the jaws upon the nut or article, as hereinafter described and claimed, the object being to furnish a wrench that can be more readily applied than socket-wrenches as heretofore made, and which will not wear the angles of a nut or cock when applied.

Reference is to be had to the accompanying drawings, forming part of this specification, in which similar letters of reference indicate corresponding parts in all the figures.

Figure 1 is a perspective view of my improved socket-wrench. Fig. 2 is a longitudinal section of the same. Fig. 3 is a cross-section on line *x x*, and Fig. 4 is a cross-section on line *y y* of Fig. 2. Fig. 5 is an end view of the wrench as made for use with six-sided nuts, Figs. 3, 4, and 5 being shown in larger size.

A is the handle portion, held on a square rod, B, by a nut, *a*, at the outer end. C is a tube or sleeve formed with an end portion, *b*, fitting snugly on the inner end of rod B, which has a flange or cap, *c*, to prevent disconnection. The cap *c* is formed with a square loop or socket, *d*.

D are the jaws within the sleeve C, and engaging the loop *d* by shoulders at their inner ends, whereby they are held by the sleeve, and are left free to open and close at their outer ends. The outer ends of jaws D are made with V-grooved clamps *l*, and the end of sleeve C is fitted with a plate, *m*, having an oblong aperture, *h*, with semicircular ends, that allows expansion of the jaws by the spring *g*, that is fitted between the jaws. The sleeve

being loose upon the end of rod B, it is free to turn independent of the jaws until by the shifting of the aperture *h* the clamps *l* are closed together. The end *b* of the sleeve is made with a flange, *i*, that may be angular for application of a wrench; or it may have a hole, as shown, for receiving a rod, K, to turn the sleeve.

In using the wrench, it is placed on the nut or bolt-head, and, the handle A being held to prevent its turning, sleeve C is turned until the clamps grip tightly on the nut, when the handle is allowed to turn with the further turning of the sleeve to move the nut.

For six-sided nuts three jaws are used, and the cam-plate *m* made with a three-point aperture, as shown in Fig. 5.

This wrench is especially adapted for turning on and off the stop-cocks of water-pipes laid in the ground, as the square on the stem of the cock can be more readily found than with a solid wrench. The clamps being made to grip tightly, the corners of the nut or square will not be worn off.

Having thus described my invention, I claim as new and desire to secure by Letters Patent—

1. In a wrench, the combination, with jaws D, held apart by a spring, of a swiveled outer tube, C, having end plate, *m*, with oblong aperture *h*, divided into two-part circles adapted to operate on the jaws, as described.

2. The combination, with the tube C, of the rod B, having the loop-socket *d*, and the jaws D, having shoulders engaging said socket, as and for the purpose specified.

3. In a socket-wrench, the combination of handle-rod B, formed with loop *d*, jaws D, engaging the loop, and the loose sleeve C, formed to close the jaws when turned, substantially as shown and described.

JAMES DAVIDSON.
